(57) **CLAIM**

The ornamental design for a motor actuator, as shown and described.

DESCRIPTION

FIG. 1 is a front view of a motor actuator.

FIG. 2 is a rear view of the motor actuator.

FIG. 3 is a left side view of the motor actuator.

FIG. 4 is a right side view of the motor actuator.

FIG. 5 is a top plan view of the motor actuator.

FIG. 6 is a bottom plan view of the motor actuator.

FIG. 7 is a perspective view showing the front, plane, and right side of the motor actuator; and,

FIG. 8 is a perspective view showing the rear, right side, and bottom of the motor actuator.

The broken lines illustrate environmental structure only and form no part of the claimed design.
